Primary Examiner — Ricky Pham(74) **Attorney, Agent, or Firm** — Andrus, Sceales, Starke & Sawall, LLP(57) **CLAIM**

The ornamental design for a chair, as shown and described.

DESCRIPTION

FIG. 1 is an isometric view of an armless chair incorporating my new design, wherein the portions in phantom illustrate environment and form no part of the claimed design;
 FIG. 2 is a front elevation view thereof;
 FIG. 3 is a right side elevation view thereof, wherein the left side elevation view is a mirror image;
 FIG. 4 is a rear elevation view thereof; and,
 FIG. 5 is a top plan view thereof.

1 Claim, 2 Drawing Sheets# US D638,641 S
